US00D580220S

(12) **United States Design Patent**
McKenzie

(10) **Patent No.:** US D580,220 S
(45) **Date of Patent:** ** Nov. 11, 2008

(54) **BARBEQUE LID**

4,430,559 A 2/1984 Rabay
4,499,630 A 2/1985 Harris et al.
D282,619 S 2/1986 Fitzgerald et al.
4,649,599 A 3/1987 Beller
4,667,652 A 5/1987 Bunton
4,924,846 A 5/1990 Peacock et al.

(75) Inventor: **Stuart T. McKenzie**, Wyevale (CA)

(73) Assignee: **Wolfedale Engineering Limited**,
Ontario (CA)

(**) Term: **14 Years**

(21) Appl. No.: **29/284,625**

(22) Filed: **Sep. 12, 2007**

(Continued)

(30) **Foreign Application Priority Data**

Sep. 5, 2007 (CA) 122176

DESCRIPTION

FIG. 1 is a perspective view of a barbecue lid showing my new design;

FIG. 2 is a top view thereof;

FIG. 3 is a front view thereof;

FIG. 4 is a side view thereof, the opposite side being a mirror image; and,

FIG. 5 is a perspective view of the barbecue lid of FIG. 1, shown in use with a barbecue.

The details shown in broken lines form no part of the claimed design.
